UNITED STATES PATENT OFFICE.

CHESTER M. PALMER, OF AURORA, ILLINOIS.

ANIMAL-SHEARS.

1,388,439.

Specification of Letters Patent. Patented Aug. 23, 1921.

Application filed September 3, 1918. Serial No. 252,385.

To all whom it may concern:

Be it known that I, CHESTER MOSES PALMER, a citizen of the United States of America, and a resident of Aurora, county of 5 Kane, and State of Illinois, have invented certain new and useful Improvements in Animal-Shears, of which the following is a specification.

My invention relates to improvements in 10 that class of animal shearing machines in which the oscillating cutter lever is mounted at a fixed angle on a pivot shaft having rotative bearing in the upper and lower walls of the shear casing or frame, and a 15 hand operated tension screw for adjusting the tension pressure on the movable cutter and the object of my present invention is to provide a means of variably increasing the adjusted tension pressure upon the movable 20 cutter in proportion to the varying cutting resistance of the hair or wool of the animal being shorn.

In the device illustrated in the accompanying drawings, the herein described improvements 25 are shown embodied in animal shears of that type covered by U. S. Patents Nos. 877,517 and 1,282,459 issued to me on January 28th, 1909, and October 22nd, 1918, both of which illustrate a hand operated tension 30 screw for adjusting the tension pressure on the movable cutter, and also a means of equalizing said tension pressure upon the different teeth of the movable cutter, while in addition to the above, my present invention 35 provides a means by which the adjusted tension pressure on the movable cutter is variably and automatically increased by and in proportion to the varying cutting resistance of the hair or wool of the animal being 40 shorn.

Most all shearing machines have a hand operated tension screw which is notched to provide a vertical adjustment of from two to five thousandths of an inch, to provide an 45 increased tension pressure as the cutters become dulled by use, and it requires about an equivalent increase of tension pressure to cut the heavier wools as smoothly as the lighter wools of an animal, and I find by 50 experiments that I can produce such required increase of tension pressure automatically, in that class of shearing machines described by making one or both of the pivot shaft bearings from four to ten thousandths 55 of an inch larger in diameter than the corresponding part of the pivot shaft, the

amount of excess play required being determined largely by the design of the machine. The usual mechanical allowance for such bearings being from one to two thousandths 60 of an inch.

In using the ordinary shearing machine, the operator usually sets the tension only 65 tight enough to cut the lighter wools smoothly, with the result that the heavier wools are partly broken or torn off leaving a ruffled and ragged appearance, or if the tension is set tight enough to cut the heavier wools smoothly, the excessive friction causes the machine to heat and dulls the cutters 70 very quickly. In operating a shearing machine embodying my present invention the tension need only be set tight enough to cut the lighter wools smoothly, the tension pressure on the movable cutter being automatically 75 increased by the cutting resistance of the heavier wools which are thereby cut smoothly, and the machine operates with a comparatively light tension while running empty.

An illustrative embodiment of this invention is shown in the accompanying drawings, in which—

Figure 1 is a plan of a pair of animal shears embodying this invention.

Fig. 2 is longitudinal sectional elevation of same taken on line 2—2 of Fig. 1.

Fig. 3 is a fragmentary sectional detail taken on a line 3—3 of Fig. 2.

Fig. 4 is substantially a section taken on 90 line 4—4 of Fig. 2;

Fig. 5 is a fragmentary view, partly in section, showing a modified arrangement of the shaft in its lower bearing;

Fig. 6 is a bottom view of the parts shown 95 in Fig. 5.

Similar numerals refer to similar parts throughout the several views.

Secured to the forward end of the casing or frame 1 is the comb or fixed cutter 6 in contact with which the movable cutter 5 is adapted to be oscillated by the lever 3 which is centrally mounted on a pivot shaft 2 which is rotatively journaled in bushings 7 and 8 having screw threaded connection respectively with the upper and lower walls of the frame 1.

The pivot shaft 2 has upper and lower cylindric portions which have rotative bearing respectively with the bushings 7 and 8 before referred to, and extends through a vertical opening 11 in said cutter lever, an

annular shoulder 9 and a flat sided shoulder 10 are formed on the shaft near the middle thereof but spaced apart axially so that when the shaft 2 and the lever 3 are assembled the 5 shoulder 9 will fit in the tapered bore 11 at a point below the longitudinal center of the lever 3 and the shoulder 10 will contact with a flattened surface or shoulder 12 formed on the lever 3 above said longitudinal center, 10 forming a vertically separated two point contact between the said shaft and lever to maintain them at a fixed angle, and the latter is adapted to rock slightly relatively to the shaft, so that the forked end of the lever 15 will bear uniformly on the movable cutter 5. Said lever 3 is provided at its rear end with a vertical socket 14 in which operates a ball 4 mounted on a crank pin extending forwardly and eccentrically from the driving 20 crank shaft 15, whereby oscillatory motion is given to said cutter lever and the cutter carried thereby, through the rotary action of said shaft.

The tension exerted on said cutter lever to 25 maintain the movable cutter in proper relation to the fixed comb, or cutter is effected through the pivot shaft 2, and the construction and arrangement of the parts are such that the oscillatory cutter lever is maintained 30 at all times at a fixed angle to the pivot shaft 2 and all tension applied thereto is exerted on the front end of the lever to hold the movable cutter against the fixed cutter, while the rear end of the lever is free from engagement with a friction surface. The construction of the parts, however is such that the cutter lever is free to rock slightly on its longitudinal axis to permit it to properly adjust itself and the cutter carried thereby, to 40 maintain a uniform contact of the movable cutter with the fixed comb or cutter as has been fully set forth and claimed in my Patent No. 877,517, issued January 28th, 1909.

The manually operated tensioning means 45 comprises an internally threaded cap 16 and a pin 17 interposed between the said cap and the shaft 2. The cap 16 has threaded engagement with the bushing 7 in axial alignment with the shaft 2 and is provided with 50 a notched flange 18 with which the spring 19 coacts for yieldingly holding the cap in any position to which it may be adjusted. The upper end of the pin 17 is formed with a ball end which engages with a corresponding socket formed in the cap 16. The lower end of the pin protrudes into a bore 22 extending inwardly from the end of the shaft 2 and rests upon a ball 23 seated in the bore 22. The diameter of the pin 17 is less than 60 that of the bore 22 and by reason of the pivotal mounting of the pin 17 there is the least possible amount of resistance to the shifting of the shaft 2 which will be more fully explained.

65 To provide a means of automatically in-

creasing the adjusted tension pressure on the movable cutter, as is required to cut the heavier wools of an animal smoothly, either the upper bearing 7 or the lower bearing 8 or both bearings are formed from four to 70 ten thousandths of an inch larger in diameter than the corresponding part of the pivot shaft 2, the amount of such excess play required depends largely on the design of the machine. It will be understood that it will 75 require less excess play if provided in both of the bearings than if in one only.

In the device shown in Fig. 2 the upper bearing 7 is formed from seven to ten thousandths of an inch larger in diameter than 80 the corresponding part of the shaft 2 and the lower bearing 2 is formed with the usual mechanical allowance of from one to two thousandths of an inch play.

Referring now to Fig. 2 for an explanation 85 as to why the provision of a certain amount of excess play between the pivot shaft and its bearings affords the desired automatic increase of tension pressure upon the movable cutter required to cut the heavier wools of 90 an animal smoothly, it will be seen that the shaft with the adjustable tension normal rests at its upper end against the rear face of the bearing in the bushing 7 and at its lower end against the front face of the bearing formed in the bushing 8. This condition is due to the fact that the tensioning force is made effective upon the lever 3 through the medium of the vertically separated two point contact of the shaft 2 with the lever 3. 95 The pivot shaft 2 bears upon only a very small arc of the bearing surface formed in the bushing 7 having a free space on each side and in front of the shaft as is clearly shown in Fig. 4, allowing the upper end 100 of the shaft to be shifted laterally and thereby forwardly under the influence of the rotating crank pin and ball 4 which applies its force to the lever 3 in a lateral direction. The direction of the shifting or tilting of the shaft laterally corresponds at all times to the direction in which the crank pin is at that time applying lateral pressure upon the lever, and the greater the force applied laterally 110 to the lever due to the cutting resistance of the hair or wool being cut, the greater the shifting of the shaft laterally and forwardly at the upper end, and rearwardly at the lower end if excess play is provided in the lower bearing, thereby increasing the tension pressure 115 on the movable cutter in proportion to the force required to oscillate the said cutter lever.

The usual allowance of play provided in 120 the pivot shaft bearings of shearing machines of the class described does not produce any comparative or practical increase of tension, but the greater the amount of excess play provided the greater will be the increase of tension pressure in proportion to 125 130

the cutting resistance of the hair or wool, and the exact amount of excess play required to provide the desired increase of tension pressure on the movable cutter to cut the 5 heavier wools of the animal smoothly, will vary in differently designed machines.

I claim:—

1. A shearing machine comprising a casing, a fixed comb or cutter, a cutter movable 10 on said fixed cutter, an oscillatory cutter lever, a pivot shaft having rotative bearing in the upper and lower walls of said casing and non-rotatively engaging between its ends said lever, one of said pivot shaft bearings formed relatively larger in diameter 15 than the corresponding part of said shaft, whereby a comparatively increased tension may be provided automatically by the operation of the machine, an adjustable tension 20 screw having threaded engagement with said casing in axial alinement with said pivot shaft, a pivot pin interposed between said tension screw and pivot shaft for applying tension to the lever through said shaft, 25 means whereby the lever and the cutter carried thereby may have a slight rocking movement with respect to the shaft to permit uniform pressure of the cutter on the fixed comb, means whereby a fixed angle between 30 said pivot shaft and lever is maintained, and means for oscillating said cutter lever.

2. In a shearing machine, the combination with a casing, a fixed comb or cutter, and a cutter movable on said fixed comb, of a pivot shaft journaled at its ends in the upper and lower walls of said casing, an oscillatory cutter lever mounted at a fixed angle mediate the ends of said pivot shaft, means for 35 applying an adjustable tension pressure to said lever through said shaft, said pivot shaft bearings relatively larger in diameter than the corresponding parts of said shaft whereby a comparatively increased tension 40 may be provided automatically by the operation of the machine, means whereby the forward end of said lever and the cutter carried 45

thereby may have a slight rocking movement to permit uniform pressure of the cutter on the fixed comb, and a means of oscillating 50 said lever.

3. In a shearing machine the combination with a casing, a fixed comb or cutter, and a cutter movable on said fixed comb, of a pivot shaft having rotative bearing in the upper 55 and lower walls of said casing, an oscillatory cutter lever mounted at a fixed angle, mediate the ends of said shaft, an adjustable tension screw having threaded engagement with the casing in axial alinement with said pivot shaft, a pivot pin interposed between 60 said tension screw and said pivot shaft, to apply tension to the lever through said shaft, said pivot shaft bearings relatively 65 larger in diameter than the corresponding parts of said shaft whereby a comparatively increased tension may be provided automatically while cutting the hair or wool of an animal, means whereby the forward end of said lever and the cutter carried thereby 70 may have a slight rocking movement with respect to said shaft to permit uniform pressure of the cutter on the guard plate, and means for oscillating said lever.

4. In shearing machines, the combination 75 with a casing, a fixed comb, and a cutter movable on said fixed comb, of a pivot shaft having rotative bearing in the upper and lower walls of said casing, an oscillatory cutter lever mounted at a fixed angle mediate 80 the ends of said pivot shaft, an adjustable tension screw having threaded engagement with said casing in axial alinement with said pivot shaft, a pivot pin interposed between 85 said tension screw and said shaft to apply tension to said lever through said shaft, and means whereby the front end of said lever and the cutter carried thereby may have a slight rocking movement to permit uniform pressure of the cutter on the fixed comb. 90

Signed at Aurora this 29 day of Aug., 1918.

CHESTER M. PALMER.
